UNITED STATES PATENT OFFICE.

DE WATT PEPPER, OF NEW MILFORD, CONNECTICUT.

DESIGN FOR A COUCH-FRAME.

SPECIFICATION forming part of Design No. 36,207, dated January 27, 1903.

Application filed December 26, 1902. Serial No. 136,747. Term of patent 8½ years.

To all whom it may concern:

Be it known that I, DE WATT PEPPER, a citizen of the United States, residing at New Milford, in the county of Litchfield and State of Connecticut, have invented and produced a new, original, and ornamental Design for a Couch-Frame; and I do hereby declare the following to be a full, clear, and exact description of the invention, such as will enable others skilled in the art to which it appertains to make and use the same.

The accompanying drawing shows a front elevation of my new design.

As shown in the drawing, the leading or material features of my design consist of the sides 1, having a general scroll-like shape, the front surfaces of said sides being perfectly plain at the upper ends thereof, the lower part of this plain surface being intersected by horizontally-disposed parallel groove-like portions 2, while extending from the lowermost

intersecting grooves are series of scroll-like figures 3, which terminate at the bottom of the portions 1 in straight lines, the plain unornamented seat-frame 4, from whose extremities extend knee-like portions 5, having flute-like ornamentations 6, which extend substantially parallel with the boundaries of said knees, and the feet 7, which terminate in toe-like representations 8.

Having thus described my invention, what I claim as new, and desire to secure by Letters Patent, is—

The ornamental design for a couch-frame, as herein shown and described.

In testimony whereof I affix my signature in presence of two witnesses.

DE WATT PEPPER.
